[57] CLAIM

The ornamental design for a hedge trimmer blade, as shown and described.

DESCRIPTION

FIG. 1 is a top perspective view of the design;

FIG. 2 is a bottom plan view of the design;

FIG. 3 is a top plan view of the design;

FIG. 4 is a side elevation of the design;

FIG. 5 is an opposite side elevation of the design; and,
FIG. 6 is a perspective view of a section of the central component of the three component blade system shown in FIGS. 4 and 5.

The broken line showing of a hedge trimmer housing is for illustrative purposes only and forms no part of the claimed design.

The view of FIG. 6 has been shown detached for clarity of illustration.
